Inventor:

Gerrit Van Daam,
By *Int'l. Co., Inc.*,
Attorney.

UNITED STATES PATENT OFFICE

GERRIT VAN DAAM, OF BUFFALO, NEW YORK

WINDSHIELD CLEANER AND PROTECTOR

Application filed January 2, 1930. Serial No. 418,143.

The invention relates to windshield cleaners and protectors. The object is not only to clean the front of the windshield from moisture, snow or sleet, but also to prevent any accumulation on the surface of the glass that may impair the vision.

The invention comprises means for directing the current of air at any desired angle against the surface of the glass, with the required velocity, and when desired to heat the air to required temperature before discharging the same against or adjacent the glass.

The purpose is to provide a self-contained unit of simple construction, which shall be inexpensive to make and efficient in action.

Referring to the drawing which illustrates merely by way of example a suitable embodiment of the invention;—

Fig. 1 is a horizontal cross-section of the device associated with a windshield a portion of which is shown in section.

Fig. 2 is a vertical section on line 2, 2 of Fig. 1.

Fig. 3 is a plan view in outline, on reduced scale, showing an alternative means for mounting.

Fig. 4 is an underside view of the tube 14 with a series of slots 16 instead of a single slot 15.

Similar numerals refer to similar parts throughout the several views.

In Fig. 1 is shown a motor 7 enclosed in chamber 8, and having a shaft 9 projecting into a separate chamber 10. Upon the end 35 of shaft 9 in chamber 10 is mounted the fan or blowing element 11. Chambers 8 and 10 are shown enclosed in a single housing 12. Connecting with the housing is a nozzle formation 13 communicating with the chamber

10 and adapted to receive by frictional engagement or otherwise the tube 14. This tube 14 is provided with a slot 15, or a series of slots 16 in alignment, at or near the bottom thereof. This tube 14 may be addition-

ally supported by one or more brackets such as 17, or otherwise if required. If the tube is sufficiently light in weight it may readily be secured and supported solely by the nozzle 13. Extending from the rear of housing 12 is a tubular extension 18 communicat-

ing at one end with chamber 10, at the other end engaging with and supporting the housing 19 in which is provided the resistance or heating element 20. This housing 19 is shown as having sliding engagement with the tubular extension 18. This extension 18 is shown as extending through the glass 21 of the windshield and clamped thereto by the clamp nut 22, threaded on a special formation 23 on the tubular extension. Between the clamping nut 22 and the housing 19, the tubular extension 18 is provided with the air inlet openings 24, adapted to be opened and closed by the sliding movement of housing 19. Air inlet opening or ports 25 are also provided in the rear wall of the housing 19. Binding posts 26 are associated with the device, which are in electrical circuit with the motor 7 and the battery 31. The binding posts 26 are also connected with the contact plates 27 for engagement with the cooperating contact pieces 29 connected with the terminals of the resistance 20 and supported outside of the housing 19 and adapted to bring the heating element into circuit when the housing 19 is moved toward the windshield to close air inlet openings 24.

The usual controlling switch 32 will obviously be properly connected and conveniently positioned in the circuit between the battery 31 and the motor.

The tube 14 is provided with a bracket or arm 33 to which is attached the actuating rod 34 extending to the inner side of the windshield so that the tube 14 may be slightly rotated in either direction to alter the angle of flow of air from nozzle 15 or nozzles 16 to the windshield.

Suitable means may be provided to prevent the accidental disengagement of the tube 14 from nozzle 13; for example a collar 35 may be secured to the tube 14 to be engaged by the latch 36 on nozzle 13 controlled by spring 37.

The device may be attached to the outer frame of the car or of the windshield instead of passing through the glass thereof. In which case a bracket 38 may be used having a clamp 39 at one end for engaging the tubular extension 18, and a similar clamp 40 at the

other end for engaging a portion of the frame 41.

In operation

- 5 When the device is suitably positioned at the upper front part of the windshield and it is desired to operate the same the switch is closed, whereupon the motor drives the blower to project a current or stream of air 10 from the nozzle slot 15 or slots 16 against or adjacent the surface of the glass. The tube 14 may be slightly rocked until the most efficient angle is secured for maintaining the glass clean and clear under the then climatic 15 conditions. In some cases it will be desirable to intercept and drive off moisture by a downward current approximately parallel with the plane of the glass. This angle can be changed from time to time to secure the best 20 results. When the temperature of the atmosphere is at or below the freezing point the housing 19 is shifted to close the air inlet ports 24 and to establish electrical contact between the elements 27, 28, 29 and 30 to bring 25 the heating element 20 into circuit, whereupon all the air will be drawn through inlet ports 24' to be heated by the heating element 20 before passing to the tube 14. By such means the formation of ice upon the wind- 30 shield is prevented.

It will be understood that, in accordance with this invention, the air is not at any time under appreciable pressure, as this would tend to impair the efficiency of operation. It 35 is only necessary to secure the required velocity of the air stream or streams to intercept or remove the moisture which would otherwise impair the clear vision.

What I claim is:

- 40 1. In a windshield cleaner and protector, a self-contained unit comprising a chambered formation, a motor, a chamber enclosed motor driven fan, an air delivery pipe supported by said formation and extending from said 45 chamber and having a swiveling connection therewith and means operable to the rear of the windshield for rocking the pipe to change from time to time as required the direction of air discharge.
- 50 2. In a windshield cleaner and protector, a self-contained unit comprising a chambered formation, a motor, a chamber enclosed motor driven fan and an electrical heating resistance, an air delivery pipe extending from 55 the fan enclosing chamber, and means for moving the resistance to cut the same out of circuit.
3. In a windshield cleaner and protector, a self-contained unit comprising a chambered 60 formation, a motor, a chamber enclosed motor driven fan and an electrical heating resistance, an air delivery pipe extending therefrom, and means for shifting the resistance to cut the same out of circuit and simultaneously to open direct air ports to the fan.

4. In a windshield cleaner and protector, a self-contained unit comprising a chambered formation having associated therewith a motor, a chamber enclosed motor driven fan, a nozzle extending from said fan enclosing chamber, and an air delivery pipe having one end rotatably seated in the nozzle and supported thereby. 70

5. In a windshield cleaner and protector, a self-contained unit comprising a chambered formation having associated therewith a motor, a chamber enclosed motor driven fan, a nozzle extending from said fan enclosing chamber, an air delivery pipe having one end rotatably seated in the nozzle and supported thereby, and a latch for disengageably securing the pipe from accidental disengagement from the nozzle. 75 80

GERRIT VAN DAAM.
